PHONOGRAPH RECORDING HEAD

Lincoln Thompson, New Haven, Conn., assignor
to The Soundscriber Corporation, New Haven,
Conn., a corporation of Connecticut

Application December 27, 1945, Serial No. 637,376

3 Claims. (Cl. 179—100.41)

1

This invention relates to improvements in phonographic recording apparatus, and more particularly to an improved electromagnetic sound recording head in which a stylus-carrying armature is pivotally mounted to vibrate with respect to a fixed solenoid which is electrically energized in accordance with the sound vibrations to be recorded.

The present invention is an improvement over that disclosed in applicant's prior Patent No. 2,222,342, issued November 19, 1940, and entitled "Electromagnetic sound recorder."

In the present invention the sound recording head has a pair of pole pieces which embrace a two-piece armature formed of two vertically aligned sections, the upper section being stationary and surrounded by a short energizing coil, and the lower section being movable, and carrying the recording stylus—said armature sections being spaced from each other by a small air gap.

One object of the present invention is to provide a recording head of the above nature in which the lower stylus-carrying section of the armature is provided with an integral horizontal rearwardly-extending bearing shaft which is resiliently secured to the head frame, the stylus being free to oscillate within a rubber-like block which dampens the vibrations thereof.

A further object is to provide a recording head of the above nature having side gaps between the upper stationary armature section and the pole pieces, which gaps are filled with non-magnetic material, and are larger than the corresponding side air gaps between the movable bottom armature and the pole pieces, so as to produce a greater magnetic flux through the bottom than the top gaps.

A further object of this invention is to provide an improved electromagnetic sound recording head of the above nature which will be relatively simple in construction, inexpensive to manufacture, compact, ornamental in appearance, and very efficient and durable in use.

With these and other objects in view, which will appear as this description proceeds, there has been illustrated on the accompanying drawings one form in which the invention may conveniently be embodied in practice.

In the drawing,

Fig. 1 is a schematic view of a sound recording apparatus embodying the invention.

Fig. 2 is a longitudinal sectional view of the recording head of such apparatus.

Fig. 3 is a transverse sectional view, taken

2

along the line 3—3 of Fig. 2, looking in the direction of the arrows.

Fig. 4 is a transverse sectional view taken along the line 4—4 of Fig. 2, looking in the direction of the arrows.

Fig. 5 is a bottom view of the recording head with the base plate and casing removed to show the interior parts.

Referring now to the drawing in which like reference numerals denote corresponding parts throughout the several views, the numeral 10 indicates a vertical lower angular movable armature section of magnetic material, said lower armature section 10 having a horizontal rearwardly-extending flat section 11, the ends of which have a pair of horizontal opposed stiff torsional pins 12, 13 provided with a pair of front and rear squared blocks 14, 15 integral therewith. The blocks 14, 15 are rigidly secured, as by soldering, in a non-magnetic elliptical ring plate 16, preferably of brass.

The movable armature section 10 is provided with a square depending leg 17 having a hollow socket 18 for receiving the shank of an inclined diamond-tipped recording stylus 19 which is adapted to indent sound grooves 20 in a disk record 21 mounted on a turntable 22.

The lower movable armature section 10 cooperates with an upper stationary flat armature section 23 spaced vertically therefrom by a small air gap 24. The armature sections 10 and 23 are embraced by a U-shaped magnet including a pair of fixed L-shaped magnetic pole pieces 25, 26, between the front of which is a rectangular upper aperture 27 enclosing a relatively short solenoid coil 28 which surrounds the upper armature section 23. Above the coil 28, the pole pieces 25, 26 have inturned arms 29, 30, and below said coil inturned arms 31, 32 are provided.

The coil 28 is energized from an amplifier 33 which is adapted to receive audio-frequency currents from a microphone 34. The ring plate 16 is secured to the lower pole piece arms 31, 32 by a pair of screws 35, 36.

The upper fixed armature section 23 is spaced from the pole piece arms 29, 30 by a pair of relatively large side gaps 37, 38 which are filled by a pair of non-magnetic spacer blocks 39, 40 as shown in Figs. 3 and 4, said blocks being soldered in position. The lower movable armature section 10 is spaced from the pole piece sections 31, 32 by a pair of relatively small side open air gaps 41, 42. By means of this construction, the steady magnetic flux passing through the movable stylus-carrying armature section 10 will be

greatly enhanced, causing the sensitivity of the recording head to be at the maximum and resulting in a superior performance thereof.

It has been found that the sensitivity of the recording head will reach a maximum when the upper side gaps 37, 38 are about fifty per cent greater than the lower side air gaps 41, 42. If the upper side gaps are made larger than this, however, the sensitivity of the recording head will start to diminish because of the introduction of too much reluctance to the flow of the alternating magnetic flux. It has been found that if the upper side gaps 37, 38 are made larger with respect to the lower gaps 41, 42 more of the steady flux due to the permanent magnets will flow through the lower gaps 41, 42, than through said upper gaps.

It has also been found that there is an optimum relationship between the upper gaps 37, 38 and the lower gaps 41, 42 for maximum efficiency of the recording head. Thus, if the upper gaps 37, 38 are made too large, however, a critical point will be reached where the reluctance of said upper gaps will reduce the flux in the entire magnetic circuit. This is illustrated by the following table which give the results of tests made with a recording head embodying the present invention and using signals at 400 cycles. The size of the upper and lower gaps is expressed in inches and the power of sensitivity is expressed in decibels of the signals reproduced from the groove generated by the recording head. This table shows the effect upon the sensitivity of the recording head of variations in the upper gaps, while holding the lower gaps constant.

Upper gaps Inches	Lower gaps Inches	Power sensitivity Db.
.007	.007	-2
.010	.007	-2
.012	.007	4
.014	.007	0
.027	.007	0

It will be noted from this table that the peak sensitivity is obtained when the upper gaps are .012 inch, and that for larger upper gaps the sensitivity levels off due to the increase in the reluctance of the magnetic circuit.

The recording head is provided with a protective casing 43 within which is secured a rear block 44 of permanently magnetized material, said block being held within the sides of the L-shaped pole pieces 25, 26 by a horizontal elongated screw 45.

In order to dampen undesired resonant vibrations of the movable armature section 10, provision is made of a thick rectangular block 46 of soft yieldable resilient rubber-like material having a square central aperture 47 which is fitted tightly about the depending leg 48 of the lower movable armature 10 and preferably cemented thereto. The block 46 is held in place in a rectangular recess 49 of a non-magnetic base plate 49, detachably secured to the pole pieces 25, 26 by means of small screws 50, 51. The block 46 has a pair of side bottom ribs 52, 53 which engage the base plate 49 and serve to space the central part of said block therefrom.

It will be understood that the damping block 46 may also be composed of any of the commercial materials generally known as "elastomers," such as "printers roll," etc., within the spirit and scope of the present invention. The damping power of

such materials is due to the fact that they are somewhat plastic and have a high internal molecular resistance to flow—requiring work to alter their shapes.

5 The coil 28 is connected to the amplifier 33 by means of a pair of conductors 54, 55 which pass out of the casing in a groove 56 in the top of the base plate 49.

The recording head is connected by a flexible 10 leaf spring 57 to a horizontal recording arm 58 which is power-driven by means of a vertical shaft 59 passing through a chassis 60 above which is located the turntable 22 which is driven by a shaft 61.

15 In order to supply power to operate the amplifier 33 and the turntable motor (not shown), provision is made of a power plug 62 connected by a pair of conductors 63, 64 to said amplifier. The microphone 34 is likewise connected to the amplifier 33 by means of a pair of conductors 65, 66.

Operation

In operation, a flux of steady magnetic lines of force will pass across the upper side gaps 31, 38, the lower air gaps 41, 42, and through the upper 25 and lower armature sections 28 and 10, respectively—the magnetic circuit being completed through the pole pieces 25, 26 and the magnet block 44. The stylus 19 will be caused to vibrate laterally around the axis of the pins 12, 13 in response to the electrical oscillations supplied to the coil 28 from the microphone 34 through the amplifier.

One advantage of the present invention is that 35 the end blocks 14, 15 connected to the torsional pins 12, 13 of the movable armature section 10 are rigidly mounted in the ring plate 16, which in turn is rigidly secured to the pole pieces 25, 26. This construction causes the lower armature section 17 to be inflexible vertically, and insures that 40 the air gap 24 between the upper and lower armature sections 23 and 10 will not be diminished by the pressure of the stylus 19 upon the disk record 21.

45 A still further advantage due to the novel stiff relatively inflexible mounting of the movable armature 10 in the recording head, is that extremely accurate groove spacing will be maintained throughout the entire recording. This will prevent undesired displacements of the recording stylus under the impact of external shocks which frequently occur when flexibly mounted recording styluses are employed.

50 A still further advantage of the rigid mounting of the movable armature 10 is that it results in a high natural period of vibration of said armature. This assists in accentuating the higher frequencies of the sound waves being recorded and in attenuating the lower frequencies thereof, the desirability of which is indicated in the prior Patent No. 2,239,042 to Kleber et al. of April 22, 1941, entitled "Wave recording and reproduction." This stiff construction also avoids "over cutting" which sometimes occurs 55 when recording at slow groove speeds, by the apparatus disclosed in my prior Reissue Patent No. 22,183, issued September 22, 1942 (original No. 2,200,866 of May 14, 1940), entitled "Apparatus for recording sound on thin disks."

70 While there has been disclosed in this specification one form in which the invention may be embodied, it is to be understood that this form is shown for the purpose of illustration only, and that the invention is not to be limited to the specific disclosure, but may be modified and em-

bodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a phonographic sound recording head, a movable lower stylus-holding armature section of magnetic material, a stationary upper armature section of similar material arranged in substantial alignment with said movable armature section leaving a horizontal air gap therebetween, a permanent magnet embracing both of said armature sections leaving two pairs of upper and lower vertical side gaps therebetween, the upper side gaps being substantially larger than the lower side gaps to produce a greater magnetic flux through the lower movable armature section than the magnetic flux through the upper fixed armature section.

2. The invention defined in claim 1, in which said upper side gaps are filled with vertical blocks of non-magnetic material.

3. In a phonographic sound recording head, a movable lower stylus-holding armature section of magnetic material having a pair of front and rear cylindrical torsion rods integral therewith, a pair of squared end blocks rigidly secured to

said rods, a stationary upper armature section of similar material arranged in substantial alignment with said movable armature section leaving a horizontal air gap therebetween, a permanent magnet embracing both of said armature sections leaving two pairs of upper and lower vertical side gaps therebetween, the upper side gaps being substantially larger than the lower side gaps to produce a greater magnetic flux through the lower movable armature section than the magnetic flux through the upper fixed armature section, and an open ring plate secured to said magnet and rigidly secured to said end blocks.

LINCOLN THOMPSON.
